UNITED STATES PATENT OFFICE.

HARRY FRIEDMANN, OF BALTIMORE, MARYLAND, ASSIGNOR OF ONE-HALF TO
JOSEPH P. DEVER, OF BALTIMORE, MARYLAND.

NECKBAND FOR GARMENTS.

1,102,490.

Specification of Letters Patent. Patented July 7, 1914.

Application filed May 23, 1913. Serial No. 769,358.

To all whom it may concern:

Be it known that I, HARRY FRIEDMANN, a citizen of the United States, residing at Baltimore city, State of Maryland, have invented certain new and useful Improvements in Neckbands for Garments, of which the following is a specification.

This invention relates to neck bands for body garments and particularly to neck bands for shirts and the primary object of the invention is to provide such neck bands with an improved attachment for receiving the collar button and protecting the neck of the wearer from contact therewith.

15 A further object of the invention is to provide an attachment of the character specified of an extremely simple and economical construction.

20 A further object of the invention is to provide an attachment of the character specified, which will be very flexible and at the same time very strong.

With these objects in view, the invention consists in the improved construction, arrangement and combination of the parts of a device of the character specified, which will be hereinafter fully described, and afterward specifically claimed.

In order that the construction and operation thereof may be readily comprehended, I will now proceed to fully describe my invention in connection with the accompanying drawings, which illustrate an approved embodiment thereof, and in which

35 drawings,

Figure 1 represents, in perspective view, the upper part of a shirt provided with a neck band having my invention applied thereto. Fig. 2 is a detail perspective sec-

40 tional view of the device.

Like reference characters indicate the same parts wherever they appear in a plurality of the figures of the drawings.

Referring specifically to the drawings, 5 indicates the front, 6 the shoulders, and 7 the neck band of a body garment, illustrated in this instance as a man's shirt. The neck-band 7 is composed of three folds 8^a, 9^a and 10^a, and a flap 14^a which is formed

integral with the inner fold 8^a, the same 50 being turned over at 11^a and incloses the two folds 9^a and 10^a of the band. These last mentioned folds 9^a and 10^a and an inner fold of the flap 14^a are terminated at the top of the neck-band and all are secured 55 together by a seam 18^a. The flap is provided with a button-hole 19^a.

My attachment thus forms a flap which normally hangs down in front of the neck-band so that its button-hole 19^a will receive 60 a collar-button with the base of the button inside the flap and seated against the neck-band, thereby avoiding any possibility of its injuring the neck of the wearer, and the head of the button will project to the front 65 in handy position to be entered into the buttonhole 20 in the outer end of the neck band.

Owing to the flap shape of the attachment it can readily be turned outward to facilitate the insertion of the collar button in 70 its buttonhole, thus avoiding the extreme difficulty sometimes heretofore encountered in inserting a collar button in a neck band in which the folds are left unstitched for a short distance to form a pocket in which to 75 insert the base of the collar button, such separated folds often becoming stuck together while being laundered.

Besides the advantages enumerated for my invention, others will be apparent in 80 the use thereof and while I have specifically described the construction, arrangement and combination of the various parts, it will be obvious to those skilled in the art to which my invention most nearly appertains, that changes and variations may be made therein, without departing from the spirit and scope of the invention.

Having thus fully described my invention, what I claim and desire to secure by 90 Letters Patent of the United States is:—

In a garment having a neck-band formed of a plurality of thicknesses of material stitched together adjacent their top edges, a flap formed integral with the inner thickness of the band, turned over to inclose the remaining thicknesses of the band, and provided with a button-hole and an inner

thickness of material, said inner thickness of the flap and inclosed thicknesses of the band terminating at the top of the band, said flap being secured to the front side of the 5 band across its top side only by the stitches which unite the top edges of the thicknesses of the band.

In testimony whereof I affix my signature in presence of two witnesses.

HARRY FRIEDMANN.
